(57) **CLAIM**

The ornamental design for an eye mask with removable eye pads, as shown and described.

DESCRIPTION

FIG. 1 is a perspective view of an eye mask with removable eye pads, showing my new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof; and,

FIG. 8 is a perspective view showing an alternative configuration of an eye mask when the eye pads are separated. The broken lines in the drawings depict portions of the eye mask with removable eye pads that form no part of the claimed design.
